UNITED STATES PATENT OFFICE

2,417,004

PROCESS FOR THE MANUFACTURE OF 4-AMINOBENZENE-N₁-(3':4'-DIMETHYLBENZOYL)-SULFONAMIDE

Henry Martin and Otto Neracher, Basel, Switzerland, assignors to the firm of J. R. Geigy A. G., Basel, Switzerland

No Drawing. Application March 27, 1944, Serial No. 528,340. In Switzerland April 9, 1943

4 Claims. (Cl. 260—397.7)

1

The condensation of p-nitrobenzene sulfene chloride with acetamide and subsequent oxidation of the acetylated p-nitrobenzene sulfenamide to p-nitrobenzene sulfone acetamide is known.

However, the same interaction cannot be carried out with tetramethyl benzamide, the aromatic acids, which are rich in alkyl groups, being largely decomposed and destroyed on oxidation.

Surprisingly we have now found that the oxidation of p-nitrobenzene-N₁-(3':4'-dimethylbenzoyl)-sulfenamide can nevertheless be carried out. Of course this fact could not be presumed.

The invention is illustrated, but not limited by the following example, wherein the parts are by weight.

Example

1 part of 3:4-dimethyl benzamide is dissolved at 30°—40° C. in 10 parts of absolute pyridine and slowly heated with 1 part of 4-nitrobenzene-sulfene chloride. After a short heating on the water-bath the mixture is poured into ice-cold diluted hydrochloric acid. The precipitation thus separated is filtered, dried and recrystallised from absolute benzene. Thus colorless prisms are obtained, the same having the melting point of 158° C.

1 part of 4-nitrobenzene-N₁-(3':4'-dimethylbenzoyl)-sulfenamide is dissolved in 50 parts of acetone and, while stirring, dropwise treated at room temperature with a 3% potassium permanganate solution in acetone, until the red coloration remains unchanged. Then there is rapidly sucked off and the 4-nitrobenzene-N₁-(3':4'-dimethylbenzoyl)-sulfamide melting at 192° C. is recovered by concentration of the acetone solution. By reduction it can be converted into p-aminobenzene-sulfone-3:4-dimethyl-benzamide.

The oxidation can also be performed with hydrogen peroxide instead of potassium permanganate.

2

What we claim is:

1. In a process for the manufacture of 4-aminobenzene-N₁-(3':4'-dimethylbenzoyl)-sulfonamide, the step which consists in subjecting 4-nitrobenzene-N₁-(3':4'-dimethylbenzoyl)-sulfenamide to the action of an oxidizing agent whereby the corresponding sulfonamide is obtained.
2. In a process for the manufacture of 4-aminobenzene-N₁-(3':4'-dimethylbenzoyl)-sulfonamide, the step which consists in subjecting 4-nitrobenzene-N₁-(3':4'-dimethylbenzoyl)-sulfenamide to the action of potassium permanganate whereby the corresponding sulfonamide is obtained.
- 15 3. In a process for the manufacture of 4-aminobenzene-N₁-(3':4'-dimethylbenzoyl)-sulfonamide, the step which consists in subjecting 4-nitrobenzene-N₁-(3':4'-dimethylbenzoyl)-sulfenamide to the action of hydrogen peroxide whereby the corresponding sulfonamide is obtained.
- 20 4. A process for the manufacture of 4-nitrobenzene-N₁-(3':4'-dimethylbenzoyl)-sulfonamide, which comprises subjecting 4-nitrobenzene-N₁-(3':4'-dimethylbenzoyl)-sulfenamide to the action of an oxidizing agent whereby the corresponding sulfonamide is obtained, and then subjecting the resultant 4-nitrobenzene-N₁-(3':4'-dimethylbenzoyl)-sulfonamide to the action of a reducing agent whereby the nitro group is reduced to amino.

HENRY MARTIN.
OTTO NERACHER.
